JAMES THOMS, OF SOUTH BOSTON, MASSACHUSETTS.

Letters Patent No. 72,121, dated December 10, 1867.

TAIL-PIECE FOR VIOLINS.

The Schedule referred to in these Letters Patent and making part of the same.

TO ALL WHOM IT MAY CONCERN:

Be it known that I, JAMES THOMS, of South Boston, in the county of Suffolk, and State of Massachusetts, have invented a new and improved Tail-Piece for Violins; and I do hereby declare that the following is a full, clear, and exact description thereof, which will enable others skilled in the art to make and use the same, reference being had to the accompanying drawings, and to the letters of reference marked theron.

This invention relates to a new and improved manner of attaching the E-string to the tail-piece of a violin, as hereinafter fully shown and described, whereby a comparatively small portion of said string is wasted in case of breakage. The present plan is to attach the string directly to the tail-piece, and have it wound around the nut or pin which passes into the head, and the remainder wound up in a piece of paper, which dangles from the head of the instrument. The string usually breaks near the nut, where it becomes worn by the action or friction produced in fingering, and, in attaching it again to the tail-piece, one-fourth of the string is lost—all the portion included between the tail-piece and the point of breakage, at or near the nut.

My invention consists in attaching the E-string to the tail-board by means of a small winch, as hereinafter fully shown and described, whereby the string, when broken, may be let out and applied to the nut or pin with but a trifling loss of its length. In the accompanying sheet of drawings—

Figure 1 is a plan or top view of my invention.

Figure 2, an inverted plan of the same.

Figure 3, a detached view of a key pertaining to the same.

Similar letters of reference indicate like parts.

A represents the tail-piece of a violin, constructed and applied to the violin in the usual way, and B represents the E-string, one end of which is attached to the pin in the head of the instrument, said string passing under a wire, a, in the hole b of the tail-piece, and attached to winch or bobbin c, the shaft of which passes vertically through the tail-piece, and has a ratchet, C, on its lower end, with which a pawl, D, engages, said pawl being attached to the under side of the tail-piece, and kept in contact with the ratchet by a spring, F, as shown in fig. 2. The top of the shaft is provided with a square, to receive a key, G, by which the winch or bobbin is turned and the string wound upon it. The pawl D has a rod, d, attached to it, which rod passes up through the hole b, and by moving this rod d, the pawl D may be disengaged from the ratchet at any time, to admit of the string being unwound from the winch or bobbin.

By having the surplus length of string wound upon the winch or bobbin, it will be seen that, in case of the breaking of the string near the head of the instrument, where the breakage generally occurs, all the string that is lost is the portion included between the point of separation and the pin—a very small portion; whereas, in the usual plan of attachment, all the string is lost between the point of separation and the tail-piece, which is about one-fourth of the length of the whole string.

Having thus described my invention, I claim as new, and desire to secure by Letters Patent—

Applying a winch to the tail-piece of a violin, substantially as and for the purpose herein shown and described.
